ALFRED WOODHAM, OF NEW YORK, N. Y.

Letters Patent No. 74,185, dated February 4, 1868.

IMPROVED SKATE-FASTENING.

The Schedule referred to in these Letters Patent and making part of the same.

TO ALL WHOM IT MAY CONCERN:

Be it known that I, ALFRED WOODHAM, of the city, county, and State of New York, have invented a new and useful Improvement in "Skates;" and I do hereby declare that the following is a full, clear, and exact description thereof, which will enable others skilled in the art to make and use the same, reference being had to the accompanying drawings, forming part of this specification.

The present invention relates to the fastening of skates to the boot or shoe-sole, and to that class of fastenings which seize the boot or shoe-sole upon its sides and heel, the invention consisting in a novel arrangement of such side-clamps upon the foot-rest of the skate, and in their connection together, at corresponding points, upon each side of the skate, whereby a fastening is produced of most simple form, and its construction practical, and not liable to become disarranged or to break from use and wear. In the accompanying plate of drawings, my improvements in skates are illustrated—

Figure 1 being a side view of a skate having them applied thereto, and

Figure 2 a plan view of the under side of the foot-rest to the skate.

A, in the drawings, represents the blade or runner to the skate, and B its foot-rest, the two being secured and connected together in any suitable manner. C, clamps; placed upon the front portion, D, of the foot-rest B, one clamp upon each side of the same. These clamps extend above the edge of the foot-rest, and at their upper ends are of suitable shape to fasten or embed themselves in the edge of the boot or shoe-sole, when brought against it in any proper manner. F, slotted arms, forming part of side-clamps C, by which slotted arms the clamps are hung upon pins or studs G, in the under side of foot-rest B, so as to move out and in thereon, and thus be drawn together, or thrown apart, according to the direction in which the screw-bolt H is turned, this bolt H passing and screwing through the nuts I, swivelled to the clamp-arms F, one to each of the same, and at their inner or those ends toward each other. By swivelling the nuts I to the clamp-arms F, all strain upon the bolt H, as it is screwed in and out of the same, is relieved—an important feature in the practical operation of the side-clamps, as is obvious. L, the clamps for the heel of the boot or shoe, one being provided for each side of the heel, and both being hung upon the under side of the foot-rest at such point. These clamps L are provided with two prongs, one, M, at one end, to grasp the heel upon its side, and the other, N, to seize the heel upon its inside face or edge, under the shank, this prong, N, to each clamp, playing in and through a slot of the foot-rest, made at a suitable point therefor. Each heel-clamp, L, turns or swings upon a centre-pin, P, and by their circular slots, Q, move upon the headed studs or pins R, the two clamps being operated, that is, brought to bear against the boot or shoe-heel by their respective prongs, or released therefrom, by the screwing in and out of a screw-bolt, S, passing through nuts T, pivoted or swivelled upon them, with one to each clamp. By the swivelling of the nuts T, through which the screw-bolt S passes, as above described, such bolt is relieved of all strain, and a more perfect operation of the clamps secured, as is obvious without any further explanation.

I claim as new, and desire to secure by Letters Patent—

1. The heel-clamps to the skates when constructed as described, to grasp the heel both upon its sides and edge, under the shank, as herein shown and described.
2. In combination with the above, I claim the pivoted slotted clamps C, when provided upon their inner ends with the swivelled right-angular nuts I, receiving the screw-bolt H, whereby the said clamps are permitted to adjust themselves to the sole of the boot or shoe, by combined lateral and longitudinal movements, as herein shown and described.

ALFRED WOODHAM.
